WILLIAM A. CHRYST, OF DAYTON, OHIO, ASSIGNOR TO DELCO-REMY CORPORATION, OF ANDERSON, INDIANA, A CORPORATION OF DELAWARE

IGNITION TIMER

Application filed February 15, 1929. Serial No. 340,114.

This invention relates to ignition apparatus for internal combustion engines, and more particularly to the automatic control of the timing of the ignition spark in response to engine operating conditions.

It is one of the objects of the present invention to provide a simple, durable and compact structure for controlling the timing of the ignition in response to variations in suction produced by the engine, and this aim of the invention is accomplished by providing an ignition timer, comprising a cam operated circuit interrupter, a drive shaft, a driven shaft operatively connected with the cam, and means responsive to engine suction for connecting the two shafts and for varying the angular relation between them, said suction responsive means comprising a piston which rotates with the shafts and slides in a cylinder concentric with the shafts and communicating with the intake of the engine.

A further object of the present invention is to provide an ignition timer having in addition to the features mentioned in the foregoing paragraph, a mechanism for controlling the timing of the ignition in response to engine speed.

Further objects and advantages of the present invention will be apparent from the following description, reference being had to the accompanying drawings wherein a preferred form of embodiment of the present invention is clearly shown.

In the drawings:

35 Fig. 1 is, in part, a vertical, longitudinal, sectional view on line 1—1 of Fig. 2, of an ignition apparatus constructed in accordance with the present invention, and in part a diagrammatic illustration of the manner of connecting the suction responsive device of the ignition timer with the engine intake.

40 Fig. 2 is a plan view of the circuit interrupter.

45 Fig. 3 is a sectional view on the line 3—3 of Fig. 1.

50 Figs. 4 and 5 are plan and side views, respectively, of the piston, which is included in the suction responsive device.

55 Figs. 6 and 7 are plan and side views, re-

spectively, of the driven shaft which is connected by the piston with the drive shaft.

Fig. 8 is a sectional view on the line 8—8 of Fig. 1.

Referring to the drawings, the ignition unit comprises a housing 20, which provides a bearing 21 for a drive shaft 22, having a journal portion 23 for supporting a driven shaft 24, which is operatively connected by centrifugal device 25 to be described later, with a circuit interrupter operating cam 26. The circuit interrupter comprises a pair of cooperating contacts 30 and 31 attached respectively to a breaker lever 32 and contact bracket 33. The lever 32 is pivoted upon a stud 34 attached to the interrupter supporting plate 35, and is insulated therefrom. The plate 35 is attached to the housing 20 by screws 36. The bracket 33 is supported upon the plate 35 and is pivotally connected with the stud 34 in order to adjust the interrupter relative to the cam 26. The lever 32 carries a rubbing block 37 which cooperates with cam 26 in order to effect the separation of the contact 30 from the contact 31. A terminal bracket 40 which is insulatingly supported by the breaker plate 35, is electrically connected with a terminal screw 41 insulatingly supported by housing 20, and is electrically connected with the lever 32 by leaf spring conductor 42 which is biased so as to urge the breaker lever 32 toward the cam 26. The spring 42 is attached to an ear 43 integral with the terminal plate 40, and is connected with a conductor 44 which is connected with one foil of a condenser which is contained within the condenser case 45. The other foil is grounded on the case which is attached to a bracket 46 secured by a screw 47 to the plate 35. The rubbing block 37 is adjusted relative to the cam 26 by moving the contact bracket 33 around the stud 34. This is accomplished by turning a screw driver slotted disk 50, which occupies a slot 51 in the bracket 33 and which has an eccentric shank 52 pivotally connected with the plate 35. The bracket 33 is clamped in the desired position of adjustment by a screw 53 which extends through an arcuate slot 54 in the bracket 33 and threadedly engages the plate 35.

The cam 26 supports a distributor rotor block 60 carrying a center contact button 61 engaging a center contact 62 in a metal cable receiving socket 63 embedded in a center sleeve 64 integral with the distributor head 65 which is supported by the housing 20 and is connected therewith by the usual spring clips not shown. The rotor button 61 is connected by a spring conductor 66 with a distributing segment 67 which rotates past a plurality of distributor posts 68 arranged in a circular row and each integral with a metal cable receiving socket 69 embedded in a sleeve 70 integral with the head 65.

15 The centrifugal mechanism 25 will now be described. This mechanism comprises a weight plate 80 attached to the knurled portion 24a of the driven shaft 24, and rotatable therewith. The plate 80 carries weight pivot 20 studs 81 about which weights 82 are rotatable. Each weight 82 has a lever arm 83 cooperating with a lever arm 84 provided by a plate 85 which is attached to the lower end of a tubular shaft 86 which provides the cam 26 25 and a support for the distributor rotor block 60. Motion of the weights outwardly due to centrifugal force is resisted by springs 87 each of which is attached to a weight pivot stud 81 and to a spring stud 88 provided on 30 each arm 84 of the plate 85. The centrifugal mechanism is designed for a circuit interrupter in which the cam 86 normally rotates clockwise as viewed in Fig. 1. As the weights move away from the shaft due to 35 centrifugal force the plate 85 will move clockwise and hence the cam 26 in order to advance the timing of the ignition spark. As the speed of the shaft 22 decreases the springs 87 will cause the weights 82 to be moved inwardly and the cam 26 to be rotated counter-clockwise relative to the shaft 24 in order to 40 retard the timing of the ignition spark.

The suction responsive device for connecting the drive shaft 22 with the driven shaft 24 includes a piston 90 which slides endwise in a cylinder 91 provided by a tubular portion integral with the housing 20, and located concentric with the shafts 22 and 24. The piston is urged upwardly by a spring 45 92 which surrounds shaft 22 and bears at its lower end against a washer 93 which is swedged into a shallow annular groove 94 in the shaft 22. The washer 93 provides an end bearing for the shaft 22 and rests upon a 50 machine surface 94a provided at the end of the shaft journal bearing 21. A short sleeve 95 spaces the lower end of the spring of the shaft 22. The upper end of the spring 92 bears against a spring retainer 96, a leather 55 packing washer 97, and presses these parts against a metal plate 98 secured by screws 99 to the lower end of piston 90. The leather washer 97 fits closely around the shaft 22 and cooperates with the piston 90 in order to 60 65 vide a suction chamber 100 within the cylinder 91. The chamber 100 is connected with the engine intake 101 by a passage 102 provided in the housing 20, an elbow 103, a pipe 104, and a passage 105 leading into the main mixture passage 106 of a carburetor 107 and located below the butterfly throttle valve 108 when in engine idling position. The valve 108 is operated in the usual manner by a throttle shaft 109 operated by a lever 110 connected by link 111 with an operating member within the reach of the driver. Obviously, increase in suction in the chamber 100 will cause the piston 90 to move downwardly and decrease of suction will permit the piston 90 to move upwardly. The longitudinal movement of the piston produces relative rotary motion between the drive shaft 22 and the driven shaft 24 due to the fact that the piston is provided with a pair of diametrically opposed longitudinal slots 85 120 which receive a pair of lugs 121 extending from the driven shaft 24, and to the fact that the piston is provided with a pair of diametrically opposed oblique slots 122, which receive lugs 123 extending from the 90 shaft 22, the lugs 123 being provided by the ends of a pin extending through the shaft 22.

When the engine is idling, the butterfly valve 108 will close the suction chamber 100 from communication from the engine intake 95 101 so that the spring 92 will maintain the piston 90 in an upward position and so that the ignition spark will be relatively retarded. Under part load conditions when the throttle 108 is partly open, the suction in 100 the intake 101 and hence in the suction chamber 100 will increase, thereby causing the piston 90 to move downwardly. As the piston moves downwardly it will rotate relative to the shaft 22 in a clockwise direction as 105 viewed from above, thereby causing the driven shaft 24 and hence the cam 26 to rotate clockwise in order to advance the timing of the ignition spark.

Likewise when the engine load is increased 110 requiring the throttle 108 to be opened wider the suction in the intake 101 will decrease and hence in the suction chamber 100. A decrease in engine suction will be accompanied 115 by an upward movement of the piston 90 due to the action of the spring 92, thereby causing the piston 90 to rotate counterclockwise relative to the shaft 22 and causing the driven shaft 24 and the cam 26 to rotate 120 counterclockwise relative to the shaft 22, in order that the timing of the ignition may be retarded.

The ignition apparatus may be readily assembled and disassembled. It comprises chiefly three sub-assemblies namely, the 125 housing 20, shaft 22 and the suction responsive device including the cylinder 91, piston 90 and spring 92; a sub-assembly including the cam 26, centrifugal mechanism 25 and driven shaft 24; and a sub-assembly includ-

ing a circuit interrupter mounted on the plate 35. Before the interrupter is in assembled position in the housing 20, the second assembly, including parts 24, 25 and 26, is mounted upon the shaft extension 23, and is connected with the drive shaft 22 simply by entering the lugs 121 of the shaft 24 in the slots 120 of the piston 90. Then the circuit breaker assembly is placed in position in the 10 housing 20 and is attached by the screws 36. Then the distributor rotor block 60 is mounted upon the cam carrying shaft 86 and the distributor head is attached to the housing 20.

15 While the form of embodiment of the present invention as herein disclosed, constitutes a preferred form, it is to be understood that other forms might be adopted, all coming within the scope of the claims which follow.

What is claimed is as follows:

1. Ignition apparatus for internal combustion engines comprising, in combination, an interrupter, a cam for operating the interrupter, a drive shaft, a driven shaft; means operatively connecting the driven shaft with the cam, and means for connecting the shafts and responsive to engine suction for varying the angular relation between them, said means comprising an endwise movable piston rotatable with the shafts, a stationary cylinder concentric with said shafts and communicating with the engine intake, and means operatively connecting the piston with both the 30 driving and driven shafts, one of said connections being such that endwise movement of the piston produces relative rotary movement between the shafts.

2. Ignition apparatus according to claim 40 1 in which the shafts are each provided with a lug and the piston is provided with grooves respectively receiving the lugs, at least one of the grooves being oblique to the axis of the shafts.

45 3. Ignition apparatus according to claim 1 in which the shafts are each provided with pairs of diametrically opposite lugs and the piston is provided with a pair of longitudinal grooves receiving one pair of lugs, and a pair of oblique grooves receiving the other pair of lugs.

50 4. Ignition apparatus according to claim 1 in which the piston is a tubular member surrounding the drive shaft, and in which a packing washer which closely fits around the drive shaft is pressed by a spring against one end of the piston, said spring being located within the cylinder and functioning to urge the piston in one direction endwise of the cylinder.

55 5. Ignition apparatus for internal combustion engines comprising, in combination, an interrupter, a cam for operating the interrupter, a drive shaft, a driven shaft operatively connected with the cam, and means for

connecting the shafts and including a member surrounding the shafts and rotatable with said shafts and having grooves receiving respectively lugs extending from the shafts, at least one of the grooves being oblique to the axes of the shafts, and engine suction responsive means for moving the member longitudinally of the shafts.

6. Ignition apparatus for internal combustion engines comprising, in combination, an interrupter, a cam for operating the interrupter, a drive shaft, a driven shaft operatively connected with the cam, and means for connecting the shafts including a tubular member movable rotatably with and longitudinally along the shafts, means for connecting the tubular member with the shafts so that movement of said member along the shafts is accompanied by relative rotary movement between the shafts, a spring for moving the member in one direction, a collar on the shaft directly receiving one end of the spring and providing a shaft end-bearing, and engine suction responsive means for moving the member in the opposite direction.

7. Ignition apparatus for an internal combustion engine comprising, in combination, a housing presenting axially aligned bearing and cylinder portions; a circuit interrupter; a cam for operating said interrupter; a drive shaft journalled in the bearing portion of the housing and extending into and through the cylindrical portion thereof; a driven shaft rotatably supported by the drive shaft; means operatively connecting the cam with the driven shaft; a rotatable and longitudinally movable piston within the cylinder portion of the housing, fitting slidably upon the drive shaft; means provided on the two shafts and engaging the piston to rotate it whereby operatively to connect the two shafts so that they will rotate together; said means producing relative rotary motion between the two shafts in response to movements of the piston longitudinally of said shafts; and engine suction responsive means for moving said piston.

8. Ignition apparatus for an internal combustion engine comprising, in combination, a housing presenting axially aligned bearing and cylinder portions; a circuit interrupter; a cam for operating said interrupter; a drive shaft journalled in the bearing portion of the housing and extending into and through the cylindrical portion thereof; a driven shaft rotatably supported by the drive shaft; means operatively connecting the cam with the driven shaft; a rotatable piston within the cylinder portion of the housing, fitting slidably upon the drive shaft, said piston providing a rotating coupling connecting the two shafts causing their rotation as a unit when the piston is immovable longitudinally, longitudinal movement of the piston providing relative rotary motion between the

shafts; and engine suction responsive means for moving the piston longitudinally of said shafts.

9. In an ignition apparatus for internal combustion engines, the combination with a cylinder member having a piston member therein, one of said members being rotatable and longitudinally movable relative to the other; of a drive shaft; a driven shaft; means operatively connecting the drive shaft with the rotatable member so that said member is rotated by said shaft; means connecting the rotatable member with the driven shaft so that the said shaft is rotated by said member, said means being adapted to rotate the driven shaft relative to the drive shaft in response to longitudinal movement of the rotatable member; and engine suction responsive means for moving said rotatable member longitudinally.

10. In an ignition apparatus for internal combustion engines, the combination with a cylinder member having a piston member therein, one of said members being rotatable and longitudinally movable relative to the other; a straight, longitudinal slot in the movable member; an oblique slot in said member; a drive shaft; a driven shaft; means on the drive shaft extending into the straight slot of the aforementioned member for rotating said member with the drive shaft and permitting longitudinal movement of said member relative to said shaft; means on the driven shaft extending into the oblique slot of said member drivingly connecting said member with said driven shaft; and engine suction responsive means for moving said member longitudinally whereby its connection with the oblique slot of said member will rotate the driven shaft relative to the drive shaft.

In testimony whereof I hereto affix my signature.

WILLIAM A. CHRYST.
